(57) **CLAIM**
The ornamental design for a light fixture arm, as shown and described.

DESCRIPTION

This application contains subject matter which is related to the subject matter of commonly assigned and co-filed U.S. Design patent application Ser. No. 29/449,521, entitled "Light Fixture Trim" by Saewoo Park, and commonly assigned and co-filed U.S. Utility patent application Ser. No. 13/834,271, entitled "Arrangements of Decorative Elements, Lighting Fixtures, and Methods for Providing Illumination" by Saewoo Park, which applications are hereby incorporated in their entirety herein by reference.

FIG. 1 is a perspective view of a light fixture arm in accordance with the new design;

FIG. 2 is a front elevational view thereof;

FIG. 3 is a right side elevational view thereof, a left side elevational view being a mirror image thereof;

FIG. 4 is a rear elevational view thereof;

FIG. 5 is a bottom view thereof;

FIG. 6 is another perspective view of the light fixture arm of FIG. 1;

FIG. 7 is another perspective view of the light fixture arm of FIG. 1; and,

FIG. 8 is another perspective view of the light fixture arm of FIG. 1.

The broken lines in the drawings illustrate portions of the light fixture arm which form no part of the claimed design.

1 Claim, 8 Drawing Sheets
